UNITED STATES PATENT OFFICE.

NEILS B. ANDERSON AND JOSEPH A. BERG, OF ASTORIA, OREGON, ASSIGNEES OF ONE-HALF TO SEATTLE-ASTORIA IRON WORKS, OF SEATTLE, WASHINGTON, A CORPORATION OF WASHINGTON.

CAN SALTER.

1,416,156.

Specification of Letters Patent. Patented May 16, 1922.

Application filed October 21, 1919. Serial No. 332,338.

To all whom it may concern:

Be it known that we, NELS B. ANDERSON and JOSEPH A. BERG, citizens of the United States, and residents of the city of Astoria, county of Clatsop, State of Oregon, have invented certain new and useful Improvements in Can Salters, of which the following is a specification.

Our invention relates to appliances having for their purpose the supplying of a fixed amount of a granular material, such as salt to a series of cans or containers. The particular purpose for which this device has been designed is the supplying of the salt required to cans which are intended for the reception of fish prior to sealing.

The specific object of this invention is to provide a device of this character in the use of which a blast of air is employed to insure the delivery of the salt into the can.

In the accompanying drawings we have shown our preferred construction, and the same will be hereinafter specifically described. The features of our invention which we deem to be new and upon which we desire patent protection will be defined in the claims terminating this specification.

Figure 1 is a side view of our device showing its relationship to an incline, over which the cans are passed prior to being filled, and a can-feed controlling mechanism.

Figure 2 is a top or plan view of the same parts.

Figure 3 is a vertical section taken through the central axis of the device, the air pump and its connections being diagrammatically illustrated.

Figures 4 and 5 are plan views taken on a plane just above the rotary disk by which the supply of salt for the individual charges is delivered to the conveying chute.

In the drawings 1 represents a tank or container for a quantity of salt. This is provided with a bottom having openings, as 10, through which the salt may pass, and thus have contact with the rotating measuring plate 2. This tank 1 is supported in fixed position.

Immediately below the tank 1 is the measuring plate 2, which is mounted for rotation in a horizontal plane. The plate 2 is provided with holes 20, of a size to contain the amount of salt which it is desired to deliver to each individual container. Provision is

made whereby the plate 2 is given an intermittent rotation, thereby placing each one of the holes 20 in succession over a discharge opening 30 in a base plate 3, upon which the measuring plate 2 is mounted. This discharge opening 30 is beneath a portion of the bottom 11 of the tank which is not comprised within the openings 10. Communicating with the discharge opening 30 is a discharge chute or pipe 31, the discharge end of which is horizontally directed, or the end of which may be bent to form a horizontally-extending nozzle, as may be desired.

We have shown, in conjunction with this device, a trapway or runway 4, over which the cans 40 pass by gravity; the runway being inclined sufficient to cause the cans to roll. In connection with such a runway, means will be provided for securing a regular timing motion to the cans so that they will move at a regular rate, thereby securing the positioning of one of the cans opposite the opening to the chute 31 at the time when the salt is discharged therefrom.

The means illustrated for this purpose comprises a star wheel 42 having recesses 80 for the reception of individual cans as they are delivered from the incline 4, and rotatable by means of an intermittently oscillating arm 43 carrying a dog 44 engageable with the ratchet wheel 45 upon the same shaft as the star wheel 42. Motion is given to the arm 43 by means of a link 46 and an arm 47, which is connected with arm 62 or any other part which is oscillated therefrom, as lever 6, and these are actuated through a link 63 from a lever 64 which is pivoted at 66 and carries cam rollers or followers 65 and 68, the latter carried on an extension arm 67. A cam 69 acts to swing lever 64 at regular intervals thus oscillating the feed 95 for the feed disk 2 and that for the can spider 42.

The bottom of the tank 1 is provided with a boss 12 which is chambered at its lower side to correspond substantially with one of the measure openings 20 in the plate 2 when the plate is in position of rest. Communicating with the chamber in this boss 12, is an air conveying pipe 5. This pipe is in communication with any source of supply of air under pressure. Means are also provided whereby the air under pressure is delivered through the pipe 5 at intervals, and these

intervals are timed to correspond with the delivery of a charge of salt to the chute 31 by the proper positioning of the plate 2.

It is evident that if the plate 2 be positioned so that the feeding compartments 20 therein are in register, both with the discharge openings 30 in the base 3 and also with the air chamber formed in the boss 12, and air under pressure be admitted to such 10 chamber, this air will blow all of the salt contained in the compartment 20, and also in the chute 31, from the discharge end of the feed chute, and if at this time a can be positioned before the opening of the chute 31 15 with its open end in line therewith, this salt will be delivered horizontally into the can.

The means for controlling the blast of air is herein shown as consisting of a pump cylinder 50, having therein a piston 51, which 20 may be operated in any convenient manner, either independent of or in connection with some member of the machine which will give it a sufficient stroke at the time desired. It is also evident that this air supply connection 25 may be with a tank containing air under pressure, and the controlling mechanism consists of a valve which is automatically actuated and properly timed through mechanism of any suitable character.

30 The means illustrated for securing this comprises a pump 50 having its piston 51 operatively connected with a lever 52 pivoted at 53 and oscillated at regular intervals by a cam 54 acting upon the follower 55.

35 The means provided for rotating the feed disk 2, as herein illustrated, consist of the following: The disk 2 is provided with a series of projections or teeth 21, the same corresponding in number with the number of 40 measuring compartments 20. A pawl-carrying arm 6 is mounted to swing upon the same axis as that of the plate 2. This carries a pawl 60 held by a spring, as 61, in engagement with the outer edge of the plate 2.

45 The arm 6 has an extension or end 62, to which is connected a rod 63, which rod is periodically reciprocated in any suitable manner from the operating mechanism of the machine. The arm 47 is connected to be 50 moved with the arm 6.

55 A stop or locking dog 7 is provided; this being pivoted upon a fixed pivot at the point 70. The end 71 of this dog extends over the periphery of the disk 2. Secured to turn with the arm 7 is another arm 72, this being positioned to be engaged by a short arm 64, which is carried by, or moved in conformity with, the arm 6, which carries the feeding pawl 60. These arms 64 and 72 are so positioned that when the arm 6 is withdrawn, in order to engage another one of the projections or teeth 21, the stop dog will be forced outwardly enough to permit free turning of the disk 2.

60 65 On the forward or feeding movement of

the arm 6 the pawl 60 will engage the tooth 21 which is just in front of it and move the disk 2 a sufficient amount to pass the engaging end 71 of the retaining dog, and thus permit the wheel to be moved one tooth 70 space. In the advance movement of the arm 6 the finger 64 will be moved so as to permit the retaining dog 7 to swing inward into engagement with the disk and thus to insure stoppage of the disk 2 when 75 the feed compartment 20 gets into exact registry with the discharge opening 30. A spring, or an equivalent member, as 73, is employed for insuring the return movement of the locking dog 7.

80 In order to insure close contact between the bottom of the tank 1 and the feeding plate 2, without probability of binding the same, a spring 8 is employed for holding the tank down upon the plate. The tank 85 is mounted about a central bar 13 and the spring 8 is placed about this bar. A washer as 80, which is secured to the upper end of the bar 13, takes the thrust of the spring.

85 A tube 9 is secured in the boss 12, which 90 contains the air chamber and in alinement with the receiving end of the discharge chute 31. This is provided with a cap 90, or other means by which its upper end may normally be closed. By the use of this device it is 95 possible, if this at any time be necessary, to employ a rod for dislodging any particles of salt which may become caked in the feed compartment or in the feed chute.

95 In operating the device the disk 2 is 100 given an intermittent movement by the pawls 60 and 7, as described, or by an equivalent device. The salt is thus delivered in measured quantity to the feed chute. At the time the feed plate is brought into 105 proper position for the discharge of salt, the air is supplied through the pipe 5, thus furnishing a blast for the prompt removal of the salt.

110 The device is so constructed as to be simple to manufacture and to be easily taken care of and inspected. Its operation is such as to also secure reliability. The use of air pressure in connection with a mechanical feeder insures a prompt and complete delivery of the salt, and also makes it possible to deliver the salt into cans placed in position such that the reliable delivery of the salt by other means might be very difficult, if not impossible. By combining a pneumatic delivery with a mechanical feed, reliable and certain action is secured and the device is adaptable to use with apparatus for the handling of the cans which vary widely in their construction and principle of 115 action.

120 What we claim as our invention is:

1. A can salting device comprising means for segregating a measured charge of salt, a salt conveying pipe for receiving the charge 125

- and having a horizontally facing discharge opening, and means for supplying a blast of air behind each charge of salt to project it horizontally from said discharge opening 5 into the can.
2. In a can salting machine, a salt bin, means for segregating and delivering measured quantities of salt therefrom, a salt conveying pipe having a horizontally discharging delivery end, means for placing the cans horizontally with their open ends facing but removed from contact with said pipe, and means for supplying a blast of air to said pipe to horizontally transfer the salt across 10 the intervening gap into the cans.
3. In a can salting device, a salt bin, means for removing measured quantities of salt from the bin, a discharge pipe leading from the bin and having a horizontal discharge 15 opening, an extension alined with said pipe leading upward through the salt bin and having a readily removable closure for its upper end, and means for supplying a blast of air to said pipe above the salt.
4. In a can salting machine, in combination, means including a horizontally directed discharge nozzle for measuring and intermittently delivering a charge of salt, means for coincidentally supplying an air blast to 20 said nozzle, means guiding a series of open ended cans rolling upon their sides past the discharge nozzle, and means controlling the movement of the cans to give them an intermittent movement coinciding with the intervals between salt discharges.
5. In a can salting machine, in combination, an inclined runway down which the cans roll, means for measuring and intermittently delivering charges of salt, the salt 25 delivery means including a horizontally directed nozzle positioned opposite to the open ends of cans rolling down said runway, means for supplying a blast of air to said nozzle to project the salt therefrom into the cans, and means controlling the movement 30 of cans to give them an intermittent movement coinciding with the intervals between salt discharges.
6. In a can salting machine, means for supplying measured quantities of salt, means for successively presenting cans with open ends facing horizontally, a discharge pipe for the salt having its discharge end facing horizontally towards the open ends of the cans, and means for supplying an air blast 35 to carry the salt across the gap into the cans.
7. In a can salting machine, means for supplying measured quantities of salt, a discharge pipe having a vertical upper receiving end and a horizontal extension at its lower discharge end, means for presenting the cans with their open ends facing horizontally towards the discharge end of said pipe, and means for supplying a blast of air to the receiving end of said pipe to thereby 40 transfer the salt to the cans.
8. A can salting machine comprising means for presenting cans with an open end facing horizontally, means for segregating a measured quantity of salt, a salt conveying pipe receiving the measured charges of salt and having its discharge end extending horizontally and to register with the open ends of the cans, and means for supplying air under pressure to the receiving end of said conveying pipe to discharge the salt 45 horizontally therefrom into the cans.

Signed at Seattle, Washington, this 30th day of September, 1919.
